UNITED STATES PATENT OFFICE.

SAM T. WROE, OF FRANKSTON, TEXAS.

AUTOMATIC RATCHET TOOL.

Application filed July 25, 1921. Serial No. 487,407.

To all whom it may concern:

Be it known that I, SAM T. WROE, a citizen of the United States, residing at Frankston, in the county of Anderson and State of Texas, have invented certain new and useful Improvements in Automatic Ratchet Tools, of which the following is a specification.

This invention relates to an improved ratchet tool for attachment or detachment 10 of bolts, screws, nuts and the like.

The primary object of the improved tool is the provision of one adapted for bolt, screw, and nut adjusting use, in connection with automatic bit carrying tools of the 15 type for rotating the bit in forward or reverse directions as set forth in Patent #791,766, dated June 6, 1905, and of the "spiral ratchet screw driver" standard type, manufactured by North Bros. Mfg. Co., of 20 Philadelphia, Pa.

A further object of the improved device, is the provision of a ratchet tool of the above described character, in which the standard automatic bit rotating tool is used 25 for operating a wrench socket to fasten a nut or bolt in a quick preliminary adjustment, independent of the ratchet wrench; the improved ratchet wrench being adapted for use as a final adjusting means.

30 A further object of the invention is the provision of a device of the above described character, which can be selectively used in connection with the standard automatic bit rotating device, or used independent for rotating a bit in either direction about its axis.

Other objects and advantages will be apparent during the course of the following detailed description.

40 In the accompanying drawings, forming a part of this specification, and in which similar reference characters designate corresponding parts throughout the several views,

45 Figure 1 is a side elevation of the improved ratchet device showing the standard driving tool connected thereto.

Figure 2 is a side elevation of the apparatus shown in Figure 1, after having driven 50 a bolt element into clamping engagement with an article.

Figure 3 is a vertical cross sectional view, taken through the improved ratchet device.

55 Figure 4 is a cross sectional view taken on the line 4—4 of Figure 9.

Figure 5 is a fragmentary sectional view showing a ratchet action in the improved tool.

Figure 6 is a cross sectional view taken on the line 6—6 of Figure 5.

Figure 7 is a side elevation of a detail of the improved tool.

Figure 8 is a plan view of a wrench handle used as a detail of the improved tool.

Figure 9 is a side elevation of the improved tool when used as an independent unit.

Figure 10 is a side elevation of the working details of the improved tool.

In the drawings, wherein for the purpose 70 of illustration is shown the preferred embodiment of my invention, the letter A designates a standard tool of the above described type, for rotating a bit in either direction about its axis. An improved ratchet 75 wrench B, forming the invention herein set forth, is adapted for use in connection with the standard tool A to adjust bolts, nuts and the like; and including a bit receiving shaft C, a casing D, means E for adjustment to 80 selectively engage said shaft C for ratchet rotation about its axis in either direction, the rotation being effected manually by means of a handle structure F.

The standard tool A preferably includes 85 a handle 11, formed axially upon a housing 12, in which a mechanism is enclosed for cooperation with the spiral grooves 13 and 14, in the element 15; said element 15 having a chuck housing 16 attached upon the 90 free end thereof, adapted for normally receiving screw driver bits and the like. A shifting key 17 is adapted for sliding in a slot 18, of the housing 12, for positioning the same in an upper portion 19 of the slot 95 adjacent the handle 11, whereby upon pushing of the handle 11, the element 15 will be rotated to the right by means of the mechanism in the casing 12 engaging the spiral groove 14. The lower portion 20 of the slot 100 18 is adapted to receive the shift key 17 when adapting the mechanism in the housing 12 to ride in the spiral groove 13, for rotating the member 15 to the left for tightening a nut, bolt, or screw for attachment 105 to an article. The intermediate position 21 of the slot, as in ordinary construction of the device A, is adapted to receive the bridge piece 17, to securely lock the member 15 to the handle 11, for use of the device A in 110

the manner similar to an ordinary screw driver or socket wrench.

Referring now to the improved tool mechanism B, the bit receiving or attaching shaft C is preferably of uniform diameter throughout the major length, and provided upon its upper end with a stub shank 25, for insertion in the chuck 16 of the standard tool A. The body portion 24 is provided with an enlarged circular portion 26, preferably integral therewith; the integral portion 26, being provided upon its upper and lower faces, with series of opposing, circumferential ratchet teeth 27 and 28 respectively, arranged symmetrically about the axis of the bit shaft C.

The means E includes the supporting frame 29 formed of the upper and lower seating rings 30 and 31, adapted for arrangement adjacent the series of teeth 27 and 28 respectively; each seating ring 30 and 31 being provided with diametrically opposed projections 32 and 33, adapted for seating in the end notched out portions of spacing posts 34 and 35. Screws 36 are provided for connection of the extreme ends of the spacing posts 34 and 35, directly into the projection extensions 32 and 33 of each of the seating rings 30 and 31. The spacing posts 34 and 35 are respectively provided with intermediate recessed seats 36^a and 36, facing away from each other, and for a purpose to be subsequently set forth.

Ratchet elements 38 and 39 are respectively provided for seating in the rings 30 and 31 respectively. The ratchet members 38 and 39 are identical in formation, each including a polygonal shaped body portion 40, having an axial aperture 41 extending therethrough. The end of each polygonal body 40 is provided with an annular projecting flange 42, which are of substantially the same diameter as the diameter defining the external surfaces of the seating rings 30 and 31. The seating rings 30 and 31 are respectively provided with polygonal shaped apertures 44 and 45, adapted to slidably receive the polygonal body portions 40 of the ratchet members 38 and 39; the projecting flanges 42 of each of the members 38 and 39 overlying the outer end faces 46 and 47 of the seating rings 30 and 31. The ratchet members 38 and 39 are provided with annular series of ratchet teeth 50 and 51 respectively, which extend inwardly of the inside surfaces 48 and 49 of the rings 30 and 31. The flanges 42 of each of the members 38 and 39 are provided with a plurality of apertures therein, adapted to slidably receive the shanks 53 of the detachable screws 54, so that said screws extend upwardly from the end surfaces 46 and 47 of the seating rings 30 and 31 respectively. Spiral springs 55 are positioned intermediate said outer surfaces 46 and 47 and the heads 56 of the

bolts or screws 54, thereby resiliently maintaining the ratchet elements 38 and 39 in their seating rings 30 and 31 respectively.

In assembling the frame 29, the bit carrying shaft C is inserted through the polygonal openings 44 and 45 of the seating rings 30 and 31, until the enlargement 26 upon which the series of teeth 27 and 28 are formed, is positioned intermediate said seating rings. The ratchet members 38 and 39 are then assembled to the seating rings 30 and 31, respectively, and in the above described manner so that the series of teeth 50 on ratchet member 38 facing the series of teeth 27 to cooperate therewith when driving a screw, or tightening a nut or bolt, and in a manner to be subsequently set forth. Likewise, the series of teeth 51 of member 39 cooperate with the annular series of teeth 28 upon the enlargement 26. Spacing collars 58 and 59 are detachably mounted in predetermined spaced relation, by set screws 60 or the like, upon the disc carrying shaft C, and adjacent the outer surfaces of the ratchet members 38 and 39, whereby the frame 29 may be moved longitudinally upon the bit carrying shaft C for proper cooperation of the various series of teeth of the frame, and the teeth series of the enlargement 26.

A circular frame supporting shifting ring 61, is provided as a part of the frame 29, and is rotatably mounted in the recessed seats 36^a and 36 of the posts 34 and 35. A bayonet slot structure 62 is provided inwardly from the upper circumferential edge 63 of the ring 61; a bayonet slot 64 being provided inwardly from the other or lower marginal circumferential edge 65 of said ring 61.

A casing D, preferably of cast metal, is provided, the same comprising a cylindrical body portion 66, having a bottom 67 provided with a polygonal shaped lug 68 projecting downwardly therefrom. Longitudinal slots 69 and 70 are provided diametrically opposite upon the body 66, and extending inwardly from the top edge 71 of the casing D. Detachable set screws 72 and 73 are provided for insertion in apertures in the exterior surface of the body 66, and at predetermined spaced distances, to project from the outer circumference of the casing D.

In assembling the casing D to the frame 29, the pin 72 is detached. The frame 29, with the bit receiving shaft C assembled thereto, is inserted into the casing D, the bit receiving end 74 of the shaft C being lowered through an aperture 75 extending axially of the casing D, and through the bottom 67 and projecting lug 68. The shifting ring 61 is of just sufficient internal diameter, to comfortably receive the casing D, and permit rotation thereof about

the casing. The supporting posts 34 and 35 are maintained in secure relation within the slots 69 and 70, having certain portions thereof projecting from said slots, substantially as illustrated in Figure 9 of the drawings. A cap 76 is next detachably mounted in any preferred manner upon the upper edge 71 of the body 66, as by set screws 77; the cap 76 having an opening therethrough 10 provided with an upwardly extending circumferential flange 78, adapted to have the body 24 of the shaft C project upwardly therethrough. The projecting set screw 72 can then be attached to the casing D to permit proper operation of the improved ratchet device.

The wrench handle F is for use in cooperation with the casing D, preferably comprising an attaching head 79, and a handle 80 extending radially and longitudinally therefrom. The attaching head 79 is provided with a polygonal depression 81 therein, and having an aperture 82 extending axially therethrough. Attaching apertures 83 and 84 are provided in the head 79. The handle structure F is assembled to the casing D having the head 79 thereof disposed beneath the bottom 67, in such manner that the polygonal lug 68 is seated within 25 in the polygonal depression 81. In this position, the bit extension 74 of the shaft C projects downwardly through the aperture 82 in the head 79. Screws 85^a are provided for insertion through the apertures 83 and 35 84 of the head 79, to engage in the bottom 67 of the casing D, to securely mount the handle structure F to the casing D, so that the handle portion 80 extends radially therefrom, substantially as illustrated in the 40 drawings, and at right angles to the axis defined by the shaft C.

The chief function of the improved ratchet device, will be that of use in connection with the tightening of bolts and nuts, and of removing the same. However, the same may be used in connection with special parts to utilize the same as a tool for driving and removing screws and the like. In connection with the standard tool 45 A, the improved device B may be used as a valuable accessory or attachment to greatly facilitate the placing of clamping elements, such as bolts and nuts. In this connection, the structure 16 of the standard tool A is adapted for receiving the stem 25 of the shaft C. A chuck structure 85 is provided, for use in connection with the bit attaching means 74 of the shaft C, having a socket 86 therein, for connection in any 50 preferred manner to the attaching end 74 which extends from the bottom of the wrench head 79, substantially as illustrated in Figure 3 of the drawings. A bit 87 is provided for engagement in a socket 88, in 55 the chuck 85, in any preferred manner, as

by set screw 89, said bit 87 having a wrench head socket structure 90, detachably mounted downwardly thereon.

In use of the improved device, to tighten a bolt 91 upon an element or article 92, the device is assembled as above described, and the head of the bolt 91 properly engaged in the socket structure 90. The preliminary step, in connection with the standard tool A, is to shift the key 17 into the lower portion 20 of the housing 12, which is for the purpose of tightening a bolt element. The ratchet device B will, of course, have to be properly set to conform with the tightening of the bolt 91, and in this connection, the shift ring 61 is oscillated upon the casing D, until the bayonet slot 64 is properly arranged with the screw 73 locked therein. This operation will have the effect of shifting the entire frame 29 downwardly over 75 the bit receiving shaft C, and until the series of teeth 50 upwardly thereon are in engagement with the top series of teeth 27 upon the enlargement 26. This operation can, of course, be effected, since the shaft C 80 is maintained in substantially rigid longitudinal assembly to the casing D by means of the spacing collars 58 and 59. The bolt 91 may be easily driven into the article 92 at first; and in connection with this driving 85 of the bolt 91, the standard tool A can be used to rapidly effect the attachment of the bolt 91, in the well known manner, by simply longitudinally forcing the handle structure 11, over the spiral threaded element 15, 90 to effect very rapid rotation of the bit engaging shaft C, and the socket 90. Back-riding of the intermeshing series of teeth 27 and 50 is permitted by reason of the resilient sliding mounting of the member 95 105 38. When the bolt has been driven as far as possible by the device A, the same can be tightened to its maximum extent by the ratchet device B. The use of the device B in this connection is simple and the only 110 operation necessary, is for the operator to grasp the projecting handle 80, and to effect a left hand oscillation of the same, which has the effect of oscillating the entire casing D, and the annular series of teeth 115 50 will engage the annular series of teeth 27, on the bit engaging shaft C, to properly rotate or oscillate the socket structure 90 in a ratchet manner, to tighten the bolt 91 in its maximum clamped position, in the 120 article 92.

When desiring to use the improved device to unscrew bolts and elements of like nature, it is merely necessary to first shift the key 17 of the standard device A into 125 the upper notch 19 provided in the housing 12. This sets the device A for a movement exactly reverse to that above described for tightening of the bolt element. Likewise, it is necessary for the operator to oscillate and 130

shift the ring 61 upwardly, until the projecting set screw 72 is locked within the bayonet slot 62, substantially as illustrated in Figure 9 of the drawings. The position of the frame mechanism and the bit engaging shaft C will then be such as to intermesh the annular series of teeth 51 and 28, as is clearly shown in Figure 10 of the drawings. The operation of the device B is then a right hand oscillation to unscrew the bolt element to overcome the preliminary tightening thereof. When the bolt element has been sufficiently loosened from an article which the same engages, the device A can be brought into operation for rapidly finishing the task.

The improved device B need not necessarily be used in connection with the standard rapid attaching tool A, since a head 93 having a socket shank 94 thereon can be detachably attached to the upwardly projecting shank 25 of the bit attaching shaft C, as clearly shown in Figure 9 of the drawings. The operation of the device illustrated in Figure 9 is effected in the manner above described, with the exception that the same operates independent of any tool A.

From the foregoing, it can be seen that an improved ratchet wrench device has been perfected, which is capable of attaching or detaching bolt elements, and of such a flexible nature as to permit attachment of the rapid working standard element A. The flexible mounting of the ratchet elements 38 and 39 insure perfect working of the wrench device B.

Various changes in the shape, size and arrangement of parts, may be made to the form of the invention herein shown and described, without departing from the spirit of the invention or the scope of the claims.

I claim:

1. A tool, comprising in combination a bit carrying shaft having opposing series of attaching teeth provided thereon, a frame slidably mounted on said shaft, ratchet members in the opposite ends of said frame for engagement with the series of teeth on said shaft, means resiliently mounting said ratchet members in said frame, a casing mounted on said shaft for rotation thereabout, and means for longitudinal shifting of said frame within said casing and over said shaft for selective engagement of the ratchet members with the teeth of said shaft, to permit the rotation of the shaft through the casing in either direction about its axis.

2. In a device of the above described character, the combination with a shaft provided with opposing series of ratchet teeth thereon, spacing collars on said shaft at predetermined distances on either side

of said series of ratchet teeth, a frame slidably mounted between the collars on said shaft, ratchet teeth carried by said frame on either end thereof, a casing about said frame for rotation about the axis of said shaft, locking means for adjustment of said frame to selectively engage either series of teeth upon the ends thereof with a companion series of teeth on said shaft, and means mounted on said casing for rotation thereof to rotate the shaft in the direction determined by said locking means.

3. A device of the class described comprising a shaft, a housing, means mounting said housing upon said shaft for axial rotation and against longitudinal movement thereon, two annular series of oppositely cut ratchet teeth rigid with said shaft and disposed within said housing, a frame longitudinally slideable in said housing, a pair of ratchet members supported by said frame in said housing, and means exteriorly supported by said housing and engaging said frame for longitudinal shifting of said frame within the housing to adjustably latch the frame in position whereby a particular ratchet member may engage a particular series of shaft teeth for rotation of said shaft in one direction, said means being adjustable to interengage the other ratchet member and shaft series of teeth so that the shaft may be rotated in opposite direction.

4. A tool of the class described comprising a shaft, rotating collars mounted upon said shaft in spaced relation, a pair of oppositely disposed annular teeth series carried by said shaft intermediate said spaced collars, a frame, ratchet members each having a series of teeth thereon in inwardly facing relation, said members being carried at the ends of said frame in longitudinal sliding relation within said ends of said frame so that the teeth thereof may cooperate with the teeth provided upon said shaft, resilient means disposed upon said frame and normally maintaining said ratchet members inwardly of said frame, a housing carried by said spaced collars upon said shaft in such manner as to be rotatable axially of the shaft and maintained against longitudinal movement with respect thereto, and selective latch means carried by said housing and engaging said frame whereby the latter may be longitudinally slid intermediate the spaced collars of said shaft to selectively engage either of said ratchet members with its cooperating series of teeth on said shaft, and by means of which the shaft may be selectively rotated in either direction upon its axis.

5. In a device of the class described, the combination of a bit or wrench carrying shaft, a housing rotatably carried by said shaft in such manner as to prevent longi-

tudinal movement thereof, selectively operated clutch means within said housing cooperating with said shaft so that the latter may be moved by rotation of the housing in either direction about its axis, said means including a sleeve disposed exteriorly of the housing having bayonet slots inwardly and laterally of its marginal edges, and projections carried by said housing adapted for selective disposal within said bayonet slots.

6. In a tool of the class described the

combination with an automatic ratchet tool including a shaft which may be rotated in opposite directions, of an auxiliary tool for detachable engagement with the shaft of 15 the automatic ratchet tool, said auxiliary tool including a bit supporting shaft, and means supported by the shaft of said auxiliary tool embodying a ratchet device which will permit operation of the shaft of said 20 auxiliary tool in either direction.

SAM T. WROE.
